CAN OPENER

Idus L. Rhodes, St. Louis, Mo., assignor to Swing-A-Way Manufacturing Company, St. Louis, Mo., a corporation of Missouri

Application April 8, 1955, Serial No. 35,426

Term of patent 14 years

(Cl. D22—2)

Figure 1 is a side elevational view of a can opener showing my new design;

Figure 2 is a bottom plan view thereof;

Figure 3 is a side elevational view showing the side opposite to that of Figure 1;

Figure 4 is an enlarged fragmentary side elevational view illustrating in detail the ornamentation thereon; and

Figure 5 is a cross-sectional view taken on the line 5—5 of Figure 4.

The operating lever, support and the operating parts shown in broken lines in Figure 1 are for illustrative purposes only.

I claim:

The ornamental design for a can opener, as shown and described.
